UNITED STATES PATENT OFFICE.

JOHN F. BRODOWSKI, OF MILWAUKEE, WISCONSIN.

SASH-FASTENER.

1,379,959.

Specification of Letters Patent.

Patented May 31, 1921.

Application filed February 9, 1920. Serial No. 357,446.

To all whom it may concern:

Be it known that I, JOHN F. BRODOWSKI, a citizen of the United States, and resident of Milwaukee, in the county of Milwaukee and State of Wisconsin, have invented certain new and useful Improvements in Sash-Fasteners; and I do hereby declare that the following is a full, clear, and exact description thereof.

10 My invention relates to new and useful improvements in means for holding storm or screen sashes, or other movable members in desired positions with respect to a window frame or other support, the present structure being more particularly of that type wherein the device employed for holding the sash or other member spaced outwardly from its support, and is also adapted to lock the member against its support.

15 It is in general the object of my invention to simplify and otherwise improve the structure of devices of this character, and to increase the efficiency thereof particularly with respect to providing a positive 20 means for preventing possible disengagement of the holding device from its position locking the sash or other member against its support.

25 It is more particularly my object to provide a device of this character wherein the holding member of the device may be formed of a single length of rod having one end bent to form an attaching eye which serves to procure the locking action of the holding 30 member.

With the above and other objects and advantages in view, which will be apparent as the description proceeds, my invention resides in the novel features of construction, 35 combination and arrangement of the parts as hereinafter described and defined by the appended claims.

In the accompanying drawings:

Figure 1 is an elevational view looking 40 toward the inner sides of the sections of a pair of sash and frame rails, showing my improved device associated therewith and locking the sash rail in closed position against the frame rail.

Fig. 2 is a similar view looking from the interior of the frame and sash.

Fig. 3 is a view looking in the direction of Fig. 1, but showing the sash rail held in outwardly moved position, it being assumed 50 that the sash rail is of the normal swinging

type pivotally attached at the top of the window frame.

Fig. 4 is a transverse sectional view through the frame and sash structure looking downwardly on the device as arranged in Figs. 1 and 2.

Fig. 5 is a detail view of the keeper plate. Referring now more particularly to the accompanying drawings, 5 designates one of the vertical rails of a window frame or sash support and 6 designates the corresponding rail of a swinging sash or other member movable toward and away from the support afforded by the rail 5, said rail having the usual sliding sash guides 7 secured thereto, which, for the purpose of this invention are treated as a part of the frame rail. The outer guide 7 carries the keeper member 8 of my device, which comprises a plate having one side portion bent laterally and secured to the guide 7, said plate extending inwardly in a plane parallel to the sash member when closed.

An attaching plate 9 has one side bent laterally and secured to the sash rail 6, 80 said plate extending inwardly therefrom to lie in a plane at right angles to the plane of the keeper plate when the sash is closed and entering an open slot 10 formed in the keeper plate, the attaching plate being of 85 such width as to extend inwardly of the inner edge of the keeper plate and being provided with a longitudinal slot 11, which projects inwardly past said edge of the keeper plate, thus defining a slide portion 90 12. The holding member of my device comprises a single length of preferably cylindrical rod material 13, which has one end bent and extending through the slot 11 and providing an attaching eye 14 and slidably 95 on the sliding portion 12 of the plate.

The free portions of the holding rod are provided with holding recesses which may be formed in any suitable manner, preferably by bowing the rod as at 15, these recesses opening downwardly and adapted to receive and seat against the lower portion of the keeper plate 8 when the rod is inserted in the slot 10 of said keeper plate to thus hold the sash member in outward 105 position as shown in Fig. 3.

When it is desired to lock the sash member in closed position, the sash member is swung to such position with the securing eye of the holding rod disposed at the inner 110

end of the sliding portion 12 and hence movable past the keeper plate. The securing eye 14 is then forced outwardly on the slide member, bearing against the inner face of 5 the keeper plate, thus affording a positive lock to hold the sash in closed position. The eye moves into recessed portions 16 of the side of the slot 10 by reason of the natural resilience of the various parts of the 10 device, thus yieldably holding the eye 14 against detachment from the keeper plate by inward movement whereby accidental disengagement to release the locking connection is positively prevented. It is also 15 noted, that when the recessed portion 15 of the holding rod is engaged in the slot in the keeper plate, said portion will drop into the lower recess 16 and be thus held against accidental detachment permitting the sash to 20 close. The other point to be noted is that when the eye member 14 is engaged against the keeper plate in locking position, any outward stress on the sash member will be exerted against the portion of the eye which 25 is located between the sides of the slot 10 whereby a positive holding is effected against such outward stress, which can not be relieved to permit outward movement of the sash member without deliberate manipulation of the holding rod from its locking 30 position.

While I have shown and described an exceedingly simple, strong and durable device which will effectively hold and lock a 35 swinging sash or other member in desired positions with respect to its support, the holding member of the device constituting a single bent rod, and while the slide portion 12 of the sash attaching member is 40 formed by providing a slotted attaching plate, said slide portion may constitute any member movable through the slot of the keeper member to afford slidable pivotal connection for the holding member.

45 While I have shown and described a preferred embodiment of my invention, it will be appreciated that various changes and modifications of structure may be employed to meet differing conditions of use and manufacture, without departing in any manner from the spirit of my invention.

What is claimed is:

1. A device of the class described comprising the combination with a pair of relatively main movable parts, of a keeper member secured to one of said parts and provided with a slot, an attachment member secured to the other part and provided with a slide portion movable through the slot of 55 the keeper member, and a holding member having one portion pivotally and slidably 60

mounted on said slide member and provided with a recess adapted to receive a portion of the keeper member to hold the main parts spaced, the end portion of the holding member being engageable against the keeper member when the slide member is inserted through the slot of the keeper member, to hold said main parts together. 65

2. A device of the class described comprising the combination with a pair of relatively main movable parts, of a keeper member secured to one of said parts and provided with a slot, an attachment member secured to the other part and provided with 70 a slide portion movable through the slot of the keeper member, and a holding member comprising a rod having one end portion bent to form an eye loosely embracing the slide portion and provided with a recess 75 adapted to receive a portion of the keeper member, said eye portion being engageable against the keeper member when the slide portion of the attaching member is inserted through the slot of the keeper member. 80

3. A device of the class described comprising the combination with a pair of relatively main movable parts, of a keeper member secured to one of said parts and provided with a slot, an attachment member secured to the other part and provided with 85 a slide portion movable through the slot of the keeper member, and a holding member slidably mounted on said slide portion and engageable against the keeper member to 90 hold the parts together, the sides of the slot of the keeper member being provided with recesses adapted to yieldably seat the holding member when the slide member is passed through the slot of the keeper member. 95

4. A device of the class described comprising a pair of relatively movable main parts, a keeper plate secured to and extending laterally from one of said parts and provided with an open slot therein, an attaching plate secured to the other part, said plate having a portion movable into the slot of the keeper plate and being provided with a slot extending past the free end of the keeper plate, a holding member having an eye portion embracing the portion of the attaching plate outwardly of its slot and slidably thereon, said eye member being movable to engage the keeper plate when the attaching plate is moved into the slot of the 100 keeper plate. 105

In testimony that I claim the foregoing I have hereunto set my hand at Milwaukee in the county of Milwaukee and State of Wisconsin.

JOHN F. BRODOWSKI.
